UNITED STATES PATENT OFFICE.

GEORGE F. A. OCHS, OF NEWARK, NEW JERSEY.

ANCHORING MEANS FOR TRACK RAILS.

1,408,391.

Specification of Letters Patent. Patented Feb. 28, 1922.

Application filed May 2, 1921. Serial No. 466,002.

To all whom it may concern:

Be it known that I, GEORGE F. A. OCHS, a citizen of the United States of America, residing at Newark, in the county of Essex and 5 State of New Jersey, have invented new and useful Improvements in Anchoring Means for Track Rails, of which the following is a specification.

The object of the invention is to provide 10 an anchoring means including a block and spike for securing railroad track rails to ties of the type referred to in my former Patent No. 1,344,926 granted June 29, 1920 wherein, as a substitute for the wood or timber ties 15 now commonly used the construction embodies marginal upper and lower facing plates with an interposed filler of laminated paper or similar fibrous material treated with creosote or other preservative, suitably 20 compressed to form a material adapted for engagement by spikes and like fastening means; and more particularly the object in view is to provide an anchor block having means for splitting or spreading the end of 25 the spike for securing an effective engagement with the filler or other material of the tie, while removal of the block from the tie, for the purpose of making repairs or replacements, is facilitated; and with these ob- 30 jects in view the invention consists in a construction and combination of parts of which a preferred embodiment is shown in the accompanying drawings, wherein:

Figure 1 is a view of an anchor block and 35 spike constructed and arranged in accordance with the invention applied in the operative position to a tie of the type indicated.

Figure 2 is a vertical sectional view of the same.

40 Figure 3 is a detail in perspective of the block.

Figure 4 is a similar view of the spike.

Figure 5 is a detail view of a modified form of block.

45 The block 10 which is embedded in the tie 11 and is provided at its outer end with a shoulder or offset forming a seat 12 to extend under the edge of the metallic cover or marginal plate 13 of the tie, said tie as in 50 the construction disclosed in my former patent above-noted having the upper and lower marginal or binder plates 13 and 14 between which is interposed a laminated filler 15, a bolt 16 being extended downward through 55 the upper marginal plate 13 and into a socket

17 in the block at the said shoulder 12. The inner end of the block is provided with an extension 18 shouldered as at 19 and extending under the foot of the rail 20, the end of the extension having a reduced lip 21 under 60 which a tool such as a crow bar or the like may be inserted to lift the block out of the tie.

The block is provided with a spike seat 22 communicating with a cross channel 23 having a splitting web or wedge 24 for splitting 65 or separating the terminals 25 of the spike 26 to cause the deflection of the extremities thereof as shown in Figure 2 to insure an interlocking engagement of the spike with the block. 70

It will be understood that whereas the rounded body portion of the block, which approximates the cross sectionally semi-circular form as indicated in Figures 1 to 3 inclusive is in some respects preferable and has 75 advantages in the facility with which it may be applied to the tie, a rectangular form of block such as that in the modification shown in Figure 5 may be substituted for the same with advantage and as also shown in Figure 80 5 a plurality of spike seats 27 may be formed therein communicating with cross channels 28 having as in the previously described form the intermediate webs 29 for splitting the inner ends of the spikes. The modified 85 construction shown in Figure 5 contemplates a single block constituting a bearing or seat for the rail between the sets of spike seats, instead of duplicate or twin blocks as required in the form illustrated in Figures 1 90 to 3 inclusive.

Having described the invention, what is claimed as new and useful is:—

1. An anchoring device for attaching a rail to a tie, consisting of an anchor block 95 removably inserted in a seat in the tie and provided with a spike channel having a spike splitting wedge at the lower end thereof, the block being provided at its outer end with a countersunk seat for the reception of 100 the marginal plate of the tie.

2. An anchoring device for attaching a rail to a tie, consisting of an anchor block removably inserted in a seat in the tie and provided with a spike channel having a 105 spike splitting wedge at the lower end thereof, the block being provided at its outer end with an overhanging lip for engagement by a block removing tool.

3. The combination with a tie, of an an- 110

choring block of cross sectionally semi-circular form embedded in the tie and provided with a spike channel having a spike splitting edge at the lower end thereof, the block being provided with an extension for disposition under a rail seated on the tie and the extension having a reduced lip under

which a tool may be engaged to lift the block out of the tie, the circular contour of the block permitting sliding movement of the 10 same in the seat in the tie during the lifting operation of the block.

In testimony whereof I affix my signature.
GEORGE F. A. OCHS.
